EASY OPENING CONTAINER

Henry A. Fink, Pelham Manor, N. Y., assignor
to Continental Can Company, Inc., New York,
N. Y., a corporation of New York

Application May 10, 1937, Serial No. 141,842

2 Claims. (Cl. 220—48)

The invention relates to new and useful improvements in an easy opening sheet metal container wherein the metal is ruptured in order to give access to the contents of the container.

5 An object of the invention is to provide an easy opening sheet metal container having a container top double-seamed thereto, wherein the metal of the container top is provided with a thinned portion disposed so that the container 10 top may be ruptured and the ruptured section lifted from the container, and wherein said thinned portion is so constructed as to withstand internal pressure without rupturing while the same force, or a lesser force applied to the container top externally will rupture the thinned portion.

15 A further object of the invention is to provide an easy opening sheet metal container of the above type wherein the thinned portion is disposed so that a relatively wide opening can be formed by the rupturing of the metal to facilitate the emptying of the contents thereof.

20 A still further object of the invention is to provide an easy opening container of the above type wherein the container top has the usual depression in the region of the double seam and a further depression forming a depending vertical wall disposed well beneath the double seam, with a thinned portion in the container top located at the angle between said vertical wall and the bottom of the depression.

25 These and other objects will in part be obvious and will in part be hereinafter more fully disclosed.

30 35 In the drawing which shows one embodiment of the invention—

Figure 1 is a sectional view through a container top embodying the invention prior to the double-seaming of the container top to the container body;

40 Fig. 2 is an enlarged view of a portion of the container top shown in Fig. 1;

45 Fig. 3 is an enlarged sectional view through the upper portion of a container embodying the invention prior to the rupturing of the metal, and

50 Fig. 4 is a view similar to Fig. 3, but showing the rupturing of the container top and the lifting of the ruptured section from the container.

55 The invention is embodied in a sheet metal container which is preferably cylindrical in shape. The container includes a body portion having a bottom end double-seamed thereto. The top end is provided with the usual flange, and after the container is filled, the top end is

secured to the body portion by double-seaming and thus the container closed. This is the usual form of so-called open top container. The invention has particularly to do with the construction of the container top, whereby the container may be easily opened. The container top has the usual depression for the chuck of the double-seaming head which joins the container top to the container body. The metal of the container top is further depressed so as to provide 10 an inset depending vertical wall which is located a short distance below the double seam. The metal where the inset vertical wall joins the bottom of the depression in the container is thinned by a drawing action, and the thinned portion is so disposed that internal pressure against the bottom side of the container top will place the metal in the thinned portion under compression and the vertical wall will restrain the compression forces so that the metal is not 20 ruptured. On the other hand, when external pressure is applied to the container top inside of the vertical wall, this thinned portion is subjected to a tension strain or force which ruptures the metal, although the external force may be 25 equal to, or considerably less than the internal force.

25 The container top in the depressed portion inside of the vertical wall is preferably provided with a raised bead located a short distance from 30 the thinned portion which stiffens the metal and aids in the lifting of the section inside of the thinned portion after the rupturing of the metal has been initiated. By this stiffening of the container top, the ruptured section may be 35 readily lifted out of the container and this greatly facilitates the rupturing of the metal and the opening of the container.

40 Referring more in detail to the drawing, the invention as illustrated includes a container body 40 to which is secured the usual bottom end by double-seaming. The upper end of the container body is flanged and the container is closed by attaching thereto a container end, illustrated in the drawing at 2. This container end is provided with the usual channel portion 3 which contacts with the flange on the container end and this channel portion and flange are rolled into a double seam. The channel is provided with a plastic sealing composition so that the 50 joint between the container top and the container body is hermetically closed by the rolling of the metal parts into the double seam.

55 The container top is provided with a depressed portion forming a wall 4 which contacts with the 55

inner surface of the container body wall 1. This wall 4 extends substantially to the lower limits of the double seam. During double seaming, a chuck is inserted in the depression in contact with this wall 4, and serves as an abutment so that the seaming roll may interfold the channel and the flange into a tightly rolled double seam which is indicated at 5 in the drawing. The container top is further depressed providing an inwardly 10 and downwardly extending wall portion 6, and a vertical wall 7 depending from the lower limits of the inclined portion 6. The bottom wall of the depression 8 is integral with this depending vertical wall 7. The portion 8a of the bottom wall 15 8 of the depression is substantially horizontal. The metal between the vertical wall 7 and the horizontal portion 8a is subjected to a die action whereby the metal is drawn in thinning as distinguished from cutting. The thinnest section 20 is preferably at a line which cuts the plane of the bottom wall of the depression substantially at an angle of forty-five degrees, as indicated in Fig. 2 of the drawing. The metal in the bottom wall of the depression is raised and beaded as indicated 25 at 9.

When the container top is constructed in the manner above described, internal pressure against the container top will place said thinned section under a compression force, and this will 30 be resisted by the vertical wall 7. When, however, the container top is subjected to an external pressure in the region of the thinned section, then said thinned section is placed under a tension force. The vertical wall 7 is rigidly supported, 35 because it is close to the double seam, and there is very little spring of the metal. Comparatively little external force is necessary to rupture the metal when said force is applied close to the thinned section and inside of the same. However, internal pressure against the container end, as 40 above noted, will not rupture the thinned section.

When it is desired to open the container, a tool indicated at T in the drawing is placed against the wall 8a close to the thinned section and downward pressure applied sufficient to initiate the 45 rupturing of the metal. The tool may be of any desired character, but is preferably provided with a relatively sharp end so that it may be readily forced against the section of the metal for the initial rupturing of the same, and the metal lifted 50 so as to continue the rupturing along the thinned section, as shown in Fig. 4. The bead will strengthen the section which is to be removed, so that the prying out tool when forced beneath this inner section that is to be removed can lift 55 the same and cause the rupturing of the metal to continue along the thinned line.

From the above it will be noted that the portion of the container top which is removed is relatively large and provides a wide opening through 60 which access may be had to the container. Then again, it will be noted that the thinned section which is to be ruptured, is close to the double

seam and supported thereby so as to insure a rupturing of the metal when pressure is applied inside of the thinned section. Then again, the thinned section is disposed a slight distance in 5 from the can wall so as to facilitate the prying up of the central section by a tool laid on the double seam as a fulcrum support.

The easy opening container described above is particularly adapted for the packaging of vegetables, such as peas, corn and the like. The 10 thinned section will withstand any differential of pressure in the processing of the container, and it will, at the same time, permit the container to be easily opened by the use of any available tool which is more or less sharp, and it is not necessary to use a tool which is equipped for cutting the metal.

It is obvious that minor changes in the details of construction and the arrangement of the parts may be made without departing from the spirit of 20 the invention as set forth in the appended claims.

Having thus described the invention, what I claim as new and desire to secure by Letters-Patent, is—

1. An easy opening sheet metal container comprising a body, top and bottom ends hermetically joined thereto by double-seaming, said top end having a depression therein providing a wall contacting with the body wall of the container inside of and to the full depth of the double seam, 30 said top end being further depressed so as to form a vertical wall inset from the body wall, the metal in the container top where said vertical wall joins the bottom portion of the depression being thinned and disposed so that internal pressure 35 applied to the container top will create a compression force within the thinned portion restrained by the vertical wall, while external pressure against the container top adjacent said vertical wall will create a tension force which will 40 rupture the metal at the thinned portion.

2. An easy opening sheet metal container comprising a body, top and bottom ends hermetically joined thereto by double-seaming, said top end having a depression therein providing a wall contacting with the body wall of the container inside of and to the full depth of the double seam, 45 said top end being further depressed so as to form a vertical wall inset from the body wall, the bottom portion of said top end having an annular raised bead spaced a short distance from said vertical wall for stiffening the section which is to be removed, the metal in the container top where said vertical wall joins the bottom portion of the depression being thinned and disposed 50 so that internal pressure applied to the container top will create a compression force within the thinned portion restrained by the vertical wall, while external pressure against the container top adjacent said vertical wall will create a tension 55 force which will rupture the metal at the thinned portion.

HENRY A. FINK.
